Inventor:

Robert Kawretzke

UNITED STATES PATENT OFFICE

ROBERT KAWRETZKE, OF KLOSTER, WENNIGSEN IN DEISTER, GERMANY

INSTRUMENT FOR ADJUSTING THE TEETH

Application filed November 4, 1930, Serial No. 493,477, and in Germany November 8, 1929.

This invention relates to an instrument for adjusting or regulating the teeth in the human mouth and consisting essentially of a screw vice formed as a yoke with clamping jaws forming opposed pressure faces, one of which jaws is located at one end of the yoke and the other of which jaws is mounted on a spindle at the other end of the yoke. The jaws supported for universal movement are adapted to be secured in any given angular position. An indicating device is provided for indicating the relative spacing of the jaws.

An embodiment of the invention is illustrated by way of example in the accompanying drawing in which Fig. 1 is a side elevation and Fig. 2 a plan to a larger scale.

Figure 3 is a sectional view of spindle 5.

Figure 4 is a fragmentary top plan view 20 of a portion of the yoke and a portion of the spindle.

The instrument has a handle 1 and a yoke 2 at one end of which is disposed the jaw 3 to press against the tooth to be adjusted or straightened and at the opposite end of which is fitted the jaw 4 forming an abutment and movable longitudinally by operation of a screw-threaded spindle. The jaw 4 is interchangeably secured to a pin 6 of rectangular section which has a ball-and-socket connection 7 with the spindle 5. The jaw 3 is similarly mounted on a pin of rectangular section having a ball-and-socket fitting and being adapted to be secured by a screw so that, when the instrument is positioned in front of and behind the teeth, in consequence of the ball-and-socket-connections the jaws 3 and 4 automatically accommodate themselves to the position of the teeth and can be secured by locking the ball joints by turning the knobs 8, the friction involved being backed up by compression springs 9. The screwing up of the jaw 4 is effected by aid of a milled nut 10 received in a slot 11 formed in the yoke. In order to effect only longitudinal movement of the spindle 5 when turning the nut 10, the spindle is secured against rotation in its bearings by milling a flat 12 thereon. In order to indicate the spacing of the jaws 3, 4 the flat 12 on the spindle and

the nut 10 are provided with graduated scales as usual in micrometer gauges, as shown in Figure 4.

It is essential that the jaws 4 shall as far as possible engage only the teeth adjacent to the tooth to be treated and that, further, the jaws which are universally mounted may be secured in any given position of adjustment.

I claim:—

1. An instrument for adjusting teeth including a yoke having a handle, the yoke being formed with a socket, a pin having a ball insertible into the socket, a jaw detachably mounted upon the pin, a spring in the yoke bearing against said ball, and adjustable means bearing against the spring to bind it within the socket to thus hold the ball, pin and jaw in adjusted positions.

2. An instrument for adjusting the teeth 70 comprising a bifurcated yoke having a handle, one end of the yoke being formed with a socket, a pin having a ball insertible into the socket, a jaw detachably carried by the pin, the ball and socket permitting the jaw 75 to be adjusted into various angular relations to the yoke, means for holding the jaw in any adjusted position, a spindle extending through the opposite end of the yoke and having screw-threads, the spindle being held in the yoke from rotating movement, a nut engaging the screw-threads of the spindle and held from longitudinal movement by the yoke whereby the spindle may be adjusted toward or from the opposite end of 80 the yoke, the spindle being formed with a socket, a pin having a ball insertible within the socket, a jaw detachably mounted upon the pin, and means for holding the pin in any angularly adjusted position with relation to the spindle.

3. An instrument for adjusting the teeth comprising a bifurcated yoke having a handle, one end of the yoke being formed with a socket, a pin having a ball insertible into the 95 socket, a jaw detachably carried by the pin, the ball and socket permitting the jaw to be adjusted into various angular relations to the yoke, means for holding the jaw in any adjusted position, a spindle extending 100

through the opposite end of the yoke and having screw-threads, the spindle being held in the yoke from rotating movement, a nut engaging the screw-threads of the spindle and held from longitudinal movement by the yoke whereby the spindle may be adjusted toward or from the opposite end of the yoke, the spindle being formed with a socket, a pin having a ball insertible within the socket, 10 a jaw detachably mounted upon the pin, and means for holding the pin in any angularly adjusted position with relation to the spindle, the last named jaw extending transversely of the spindle and being curved on its face 15 confronting the opposite jaw, the opposite jaw having a width less than the length of the first-named jaw and being disposed in a plane midway of the first-named jaw.

In testimony whereof I hereunto affix my
20 signature.

ROBERT KAWRETZKE.
